DESIGN FOR A COVER FOR AN ELECTRIC ROASTER OR THE LIKE

William J. Russell, Mansfield, Ohio, assignor to
Westinghouse Electric & Manufacturing Com-
pany, a corporation of Pennsylvania

Application April 13, 1940, Serial No. 91,658

Term of patent 7 years

To all whom it may concern:

Be it known that I, William J. Russell, a citizen of the United States, residing at Mansfield, in the county of Richland and State of Ohio, have invented a new, original, and ornamental Design for a Cover, for an Electric Roaster or the like, of which the following is a specification, reference being had to the accompanying drawing, forming part thereof, in which:

Figure 1 is a perspective view, looking down from the top, of a cover, for an electric roaster or the like, showing my design; and

Figure 2 is a top plan view thereof.

The characteristic feature of the design resides in the cover for an electric roaster or the like of the configuration shown having the plate of glass at the central portion of said cover, as shown.

I claim:

The ornamental design for a cover for an electric roaster or the like, substantially as shown and described.

WILLIAM J. RUSSELL.
